UNITED STATES PATENT OFFICE.

NATHAN OTTINGER, OF NEW YORK, N. Y.

CORRESPONDENCE DEVICE.

1,242,968.

Specification of Letters Patent. Patented Oct. 16, 1917.

Application filed October 5, 1915. Serial No. 54,115.

To all whom it may concern:

Be it known that I, NATHAN OTTINGER, a citizen of the United States of America, and a resident of the borough of Manhattan, in the city, county, and State of New York, have invented certain new and useful Improvements in Correspondence Devices, of which the following is a specification.

The present invention relates to improvements in correspondence means and particularly to a device combining the functions of letter paper and envelops, containing upon itself both the address of the addressee and the written or printed matter forming the subject of the correspondence, and which can only be opened by breaking the seal, or, when unsealed, by utilizing the opening device.

An object of the invention is to provide an article of this character which may be readily and conveniently placed in a type-writing machine, or written by hand, and the entire letter written and addressed in a single operation, thereby resulting in a great saving of time and paper, impossibility, as under the present method of using paper and envelops, of confusing envelops and letters, and obviating the necessity of writing the addressee's name and address twice as with the old method of having envelops and letters. Another object is to preserve in a single sheet the address portion and paper, thereby keeping as a future reference post-marks, dates, etc. A still further object is to provide such a device which may, though it need not be manufactured from a single sheet of paper, and which will be simple in construction and inexpensive to manufacture.

With these and other objects in view, my invention is shown in the accompanying drawings, and will be hereinafter more fully described with reference thereto and finally pointed out in the claims.

In the accompanying drawings.

Figure 1 is a plan view of an embodiment of my invention, showing the blank before folding;

Fig. 2 shows the retaining or address portion folded and the device ready to be written upon;

Fig. 3 is a perspective view showing the

method of inserting the lower portion of the sheet into the retaining member.

Fig. 4 shows the device folded and ready for mailing.

Fig. 5 shows a modified form in which the retaining portion has a diagonal shape.

Fig. 6 is a plan view of a modified form of my invention with locking means;

Fig. 7 shows the same folded and ready for mailing;

Fig. 8 is a detail sectional view showing the locking means enlarged;

Fig. 9 is a plan view of a modified form of the construction so made as to afford additional writing space, by an elongation of the sheet with suitable folds so as to fold easily within the retaining portion;

Fig. 10 is a plan view of another modified form of construction;

Fig. 11 shows the same folded and ready for mailing;

Fig. 12 shows a further modified form with the retaining portion folded and the device ready to be written upon;

Fig. 13 shows the form folded and ready to be mailed;

Fig. 14 shows another modification in which two foldings of the paper are necessary;

Fig. 15 shows the same folded once;

Fig. 16 shows the same folded twice and ready for mailing;

Fig. 17 shows still another modified form, in which the folded device has a triangular shape; and

Fig. 18 shows the same completed and ready for mailing.

Similar reference characters indicate corresponding parts throughout the several figures of the drawings.

Referring to the drawings, and more particularly to Fig. 1 thereof, a main portion 10 is provided at its upper edge with a portion 11 and at each side and along the upper section thereof with flaps or extensions 12 and 13, the flap 12 being provided with a downwardly extending flap 12^a, and adjacent the said portion 12^a the main portion 10 is provided with a notch or slit 10^a. In forming the improved correspondence means from the blank just described, the portion 11 is folded down upon the portion 10, and the

flap 12 is folded inwardly thereon, and secured by means of the extension 12^a which is bent over and pasted or otherwise fastened to the under side of the portion 10. The 5 contacting portions of the flap 12 and the portion 11 are pasted or otherwise fastened together, thereby forming a pocket for the reception of the lower part of the portion 10. The right hand side of the portion 11, 10 it will be noticed, is open to permit the insertion of such lower part as clearly illustrated in Fig. 3. The portions 11, 12 and 13, or any of them, in this or any of the foregoing forms, may be given a diagonal or any 15 other shape not inconsistent with the performance of similar functions, the diagonal shape being illustrated in Fig. 5. The flap 13 is suitably gummed, and is preferably provided with a thread or wire 13^a embedded 20 in such gum to permit the device to be readily opened, as hereinafter more fully pointed out. Other substantially equivalent opening means may be employed. A slot 13^b is provided transversely in said flap 13, adjacent 25 the lower edge of the portion 11 and extending from the outer edge partially across the said flap, the remaining portion being perforated, as at 13^c. This construction facilitates opening of the device when the same is 30 sealed, as hereinafter described.

In the form illustrated in Fig. 2, and in which this embodiment of the invention will be marketed, the same may be readily placed in a typewriting machine, printing press, or 35 the like, or may, if desired, be written out in long hand. The name and address is written on the portion 11 and the body portion of the letter on the portion 10. If further writing space is required than is permitted by the size of the paper, the portion 40 10 may be lengthened by as many added sections as desired or the device shown in Fig. 9 may be used, or additional sheets may be readily inserted, and any inclosures such as 45 coins or papers may, if desired, be inserted without danger of loss.

When the letter is completed, the portion 10 is folded intermediately, which may be along the line of a prepared fold or score 50 line, and is placed within the pocket formed by the portions 11 and 12, one method of insertion, namely by a rotary movement as shown in Fig. 3. The gummed flap 13 is pasted down, as indicated in Fig. 4, upon 55 the portions 10 and 11, and the device is thereby sealed and ready for mailing.

When the device is to be opened, the thread 13^a is pulled, severing the sealed portion, and the short perforated portion 13^c is 60 torn, whereupon the letter may be readily unfolded and any inner sheets or other contents readily removed.

In Figs. 6, 7 and 8 I have shown a slightly modified form of construction, in which I 65 employ a locking device. In this form the

portion 12 is folded inwardly upon 10 and the portion 11 is folded down upon it and pasted or otherwise fastened at the contact points while the flap 12^a is bent and pasted or fastened on the underside of the portion 70 10. The lower left hand corner of the portion 10 is slightly rounded, as at 15, the outline of this rounded portion being substantially coincident with an arc described with the point w as a center. There is provided a 75 slot or cut-out portion 15^a formed at an inclination slightly greater than the rounded portion 15 and at substantially an inclination of 30°. The entrance of this cut-out portion 15^a is flared, as at 15^b. An obstruction 80 15^c is provided in the pocket formed by the portions 11 and 12, and also at an angle of substantially 30°, but in the opposite direction, when the slot and obstruction are brought into coöperation as hereinafter 85 pointed out. This obstruction may be of paper, staples, gumming, stitching or other suitable means. When the lower portion of the sheet is placed in the pocket this obstruction 15^c is engaged by the inclined cut-out 90 portion 15^a, so that its ends abut each side of the portion 15^a substantially above the entrance. When the device is sealed, it is impossible without tearing of the same to force the locked portion out of the pocket 95 to read the contents thereof. As soon as any pull is exerted on the letter, a binding or wedging effect is caused between the inclined obstruction and the oppositely inclined slot which forms a positive lock. 100 When the device is unsealed, the same may then be readily removed. If desired, the obstruction and the flap formed by the cut-out portion 15^a may be suitably reinforced, so as to strengthen the contacting edges. 105

In Fig. 9 I have shown a method of providing additional writing space where the space provided in the ordinary form is not sufficient for the correspondence intended to be written, and while I have illustrated the same with reference to the form shown in Figs. 6, 7 and 8, it will be understood that the same may be used with any of the other forms. In this form, the upper and lower parts of the portion 10 are spaced apart by intermediate sheets 15^d formed integral with said upper and lower portions. When the correspondence is completed, the same is folded along the dotted lines shown, which may be previously prepared folds or score 115 lines, and the same may be locked and sealed in the usual manner.

In the form shown in Figs. 10 and 11, a slightly modified form of locking means is employed which comprises a V-shaped obstruction 16 formed in the pocket and a cut-out portion 16^a provided in portion 10, the cut-out portion having a truncated V-shaped projection 16^b therein, which upon folding 120 of the letter engages the obstruction 16 and 125 130

locks the letter against being pushed or otherwise manipulated out of the pocket without tearing. The left hand corner of the portion 10 is rounded as in the foregoing construction, shown in Figs. 6 to 9. In this form, I have shown additional writing sheets formed integral with the portion 10, and which may be folded therewith along previously prepared lines of folding or score lines and placed beneath the retaining means. These additional sheets comprise a portion 16^c extending at the right of the lower part of the portion 10 and a portion 16^d extending upwardly from the portion 16^c. The portion 16^c is of a width corresponding to the width of the portion 10, less the width of the portion 12, and the portion 16^d is less than the portion 16^c an amount corresponding to the width of the portion 13. When the letter is completed, the portion 16^d is folded downwardly upon the portion 16^c, and this is then folded inwardly upon the portion 10, whereupon the device may be closed in the ordinary manner. In this form, instead of the slot 13^b, I have provided perforations 16^e in the portion 13. Other forms of locking means performing substantially the same purpose as those hereinbefore shown, may be employed.

In Figs. 12 and 13, I have illustrated a form of my invention intended for open or unsealed letters, such as circulars, advertisements, business announcements, etc. In this construction, the pocket is formed in a similar manner to that illustrated in Figs. 1 to 4, with the exception that the right hand edge of the portion 11 is closed by means of an extension 17, and the lower right hand corner of the portion 10 is rounded, as at 18. An ungummed flap 19 is provided at the right hand side of the upper section of portion 10, having an upwardly extending portion 20 thereon. When the letter is completed, the same is folded in a manner similar to that described with reference to the forms shown in Figs. 1 to 4, and thereupon the ungummed flap 19 is folded over and the extension 20 inserted under the portion 11, as clearly shown in Fig. 13. This construction securely maintains the letter closed for all ordinary purposes, while at the same time it may be readily opened when desired.

In Figs. 14 to 16, I have shown a form of my invention requiring a double folding of the paper. An enlarged sheet 21 is provided along the left half of its upper edge with a portion 22 having an extension 22^a thereon, and along the upper half of the left edge of the sheet 21, a portion 23 having an elongated slot 24 along the folding line thereof is provided. The portion 22 is provided along its upper edge, and between such edge and the extension 22^a, with a cut-out portion 22^b which registers with the slot 24

when the device is folded. A gummed flap 25 is provided on the right hand edge of the sheet 21 opposite the slot 24, having a thread 26 along the folding line thereof. In forming the device, the flap 23 is folded inwardly upon the portion 21 and the portion 22 is folded downwardly thereon, the extension 22^a being pasted or otherwise fastened to the underside of the portion 21, and the contacting portion of the flap 23 and portion 22 being pasted or otherwise fastened together.

When the letter is completed, the portion 21 is first folded along the longitudinal line of folding and inserted beneath the pocket, and is then folded along the vertical line of folding, whereupon the gummed flap 25 may be passed through the slot 24 and pasted to the underside of the portion 21. This form permits the use of a large sheet of paper, or if desired, a relatively smaller retaining portion.

In Figs. 17 and 18, I have shown a still further modified form, in which the folded device has a triangular shape. The blank from which this is formed is constructed in the shape of a square 27, provided at the upper edge with a flap 28 and at the left edge with a flap 29. The flap 29 is folded upon the square 27, and the flap 28 is folded down and pasted or otherwise fastened along the contacting portion to the flap 29, thereby forming a pocket. While it will remain closed of itself, a slot 30 is provided in the upper left hand corner of the pocket, formed by the flaps 28 and 29, and a gummed tab or flap 31 is provided at the lower right hand corner of the sheet 27, which upon folding of the paper from corner to corner along the dotted lines indicated, is placed in the said slot and pasted upon the outer side of the pocket to seal the device.

The slot and gummed flap for sealing or closing may be placed in any position on the flap or flaps forming a pocket, or on the body of the sheet.

With this present invention, a very inexpensive improved correspondence device is produced (adapted for all kinds of correspondence including letters, telegrams, bill heads, or other correspondence), which may be, but need not be, stamped or cut from a single piece of paper, and will prove efficient and practical in use. The present invention possesses many advantages. Among these advantages are the following.

With my improved device, it will be noted that all matters recorded upon the device, such as post-marks, etc., are inseparably preserved, thus preventing lawsuits or other disputes arising out of the question of the date of mailing or receipt of a particular letter or the substitution of the contents.

The necessity of writing the name and address of the addressee more than once is avoided, and also the mistakes which some-

times happen under the old system, of writing the name and address differently upon the envelop than upon the letter. After the letter is written, the same may be closed with a single folding and sealing operation, and made ready for delivery, forming an absolutely closed pocket, in which may be placed any foreign matters desired, such for instance, as coins, samples, etc.

16 My improved device lends itself readily to many uses, such for instance as social correspondence, telegrams, circulars, etc., and in any of these adaptations proves convenient, economical, and an efficient substitution for 15 an envelop and letter paper, usually employed.

I have illustrated and described preferred and satisfactory forms of my invention, but it is obvious that changes may be made 20 therein, within the spirit and scope thereof, as defined in the appended claims.

I claim:—

1. In a device of the character described, a sheet of material foldable to form two or 25 more folds, one of said folds having a permanent and stationary retaining member superimposed thereon, extending in one of its principal dimensions, in proximity to a considerable part of an edge, which edge is 30 adjacent a line of folding, and leaving the remainder of said sheet exposed, another fold being of a size to extend beyond the bounds of the exposed portion of the first mentioned fold and above the retaining member, a portion of such extension being insertible beneath the retaining member, a holding flap on said sheet adapted to be utilized after folding, to hold the same closed.

40 2. In a device of the character described, a sheet of material foldable to form two or more folds, one of said folds having a permanent and stationary retaining member superimposed thereon, extending in one of 45 its principal dimensions, in proximity to a considerable part of an edge, which edge is adjacent a line of folding, and leaving the remainder of said sheet exposed, another fold being of a size to extend beyond the 50 bounds of the exposed portion of the first mentioned fold and above the retaining member, a portion of such extension being insertible beneath the retaining member, a holding flap on said sheet adapted to be utilized after folding to hold the same closed, and locking means provided on said sheet beneath said retaining member, said locking means adapted to lock said sheet closed, said means permitting easy opening 55 and closing of the sheet when the said securing means is inoperative.

3. In a device of the character described, a sheet of material foldable to form two or more folds, one of said folds having a permanent and stationary retaining member

superimposed thereon, extending in one of its principal dimensions, in proximity to a considerable part of an edge, which edge is adjacent a line of folding, and leaving the remainder of said sheet exposed, another fold being of a size to extend beyond the bounds of the exposed portion of the first mentioned fold, and above the retaining member, a portion of such extension being insertible beneath the retaining member, 70 securing means on said sheet to secure it when folded in closed position, said last mentioned fold being provided with an inclined slot at one edge thereof, said inclined slot adapted to be engaged beneath said retaining member when said fold is folded, and an obstruction on said sheet beneath said retaining member, extending in oppositely inclined direction from said slot, and adapted to be engaged thereby, to lock said sheet 80 closed, said slot and obstruction permitting 85 easy opening and closing of the sheet when said securing means is inoperative.

4. A device of the character described, comprising a sheet of material foldable to 90 form two or more folds, one of said folds having a permanent and stationary retaining member superimposed thereon, said retaining member being attached, along two of its principal dimensions, in proximity to 95 a considerable portion of each of two contiguous edges of said fold, one of which edges is adjacent a line folding, each of the remaining edges of said fold being open for a considerable distance, said retaining member 100 being considerably less in area than said fold and leaving the remainder of said sheet exposed, another fold being of a size to extend beyond the bounds of the exposed portion of the first mentioned fold and above 105 the retaining member, a portion of said extension being insertible beneath the retaining member by rotary movement of said fold about the end portion of said line of folding in proximity to said retaining member, the insertible portion when inserted extending along a considerable portion of each of two edges of said first mentioned fold, one of which edges is adjacent said line of folding, the other edge being opposed to said line of folding, said retaining member 110 adapted to exert a holding force on said last mentioned fold longitudinally and transversely and holding means on said sheet adapted to be utilized after folding to 115 hold the same folded.

5. In a device of the character described, a sheet of material foldable to form two or more folds, one of said folds having a permanent and stationary retaining member superimposed thereon, said retaining member being attached, along two of its principal dimensions, in proximity to a considerable portion of each of two contiguous edges of said fold, one of which edges is ad- 120 125 130

- 5 jacent a line of folding, the other edge being opposed to said line of folding, each of the remaining edges of said fold being open for a considerable distance, said retaining member being considerably less in area than said fold and leaving the remainder of said sheet exposed, another fold being of a size to extend beyond the bounds of the exposed portion of the first mentioned fold and
- 10 above the retaining member, a portion of said extension being insertible beneath the retaining member, the insertible portion extending along a considerable portion of each of two edges of said last mentioned fold, one of which edges is adjacent said line of folding—the other edge being opposed to said line of folding, and a cut in the sheet along said line of folding at the end thereof to enable the aforesaid portion of
- 15 the last mentioned fold to be inserted beneath said retaining member.
6. In a device of the character described, a sheet of material foldable to form two or more folds, one of said folds having a permanent and stationary retaining member superimposed thereon, said retaining member being attached, along two of its principal dimensions, in proximity to a considerable portion of each of two contiguous
- 20 edges of said fold, one of which edges is adjacent a line of folding, the other edge being opposed to said line of folding, each of the remaining edges of said fold being open for a considerable distance, said sheet of
- 25 material being provided with sealing means, said retaining member being considerably less in area than said fold and leaving the remainder of said sheet exposed, another fold being of a size to extend beyond the bounds of the exposed portion of the first mentioned fold and above the retaining members, a portion of such extension being insertible beneath the retaining members, by rotary movement of said fold above the end portion of said line of folding in proximity to said retaining member, the insertible portion extending along a considerable portion of each of two edges of said last mentioned fold, one of which edges is adjacent said line of folding, the other edge being opposed to said line of folding, said retaining members exerting a holding force on said fold longitudinally and transversely and holding means on said sheet adapted to be utilized after folding
- 30 to hold the same folded.
7. In a device of the character described, a sheet of material foldable to form two or more folds, one of said folds having a permanent and stationary retaining member superimposed thereon, said retaining member being attached, along two of its principal dimensions, in proximity to a considerable portion of each of two contiguous edges thereof, one of which edges is adjacent a line of folding, the other edge being
- 35 opposed to said line of folding, said fold being open for a considerable distance along each of the remaining edges thereof, another fold being insertible beneath the retaining member by rotary movement of said fold about the end portion of said line of fold-
- 40 ing in proximity to the retaining member, and adapted to engage entirely and immediately upon the inner side of the first mentioned fold, said retaining member exerting a holding force on said fold longitudinally and transversely and holding means on said sheet adapted to be utilized after folding to hold the same folded.
8. In a device of the character described, a sheet of material foldable to form two or more folds, one of said folds having permanent and stationary retaining members superimposed thereon, said retaining members being attached, along their principal dimensions, in proximity to a considerable portion of each of two contiguous edges of said fold, one of which edges is adjacent a line of folding, the other edge being opposed to said line of folding, each of the other two edges of said fold being open for a considerable distance, said retaining members being considerably less in area than said fold and leaving the remainder of said sheet exposed, another fold being of a size to extend beyond the bounds of the exposed portion of the first mentioned fold and above the retaining members, a portion of such extension being insertible beneath the retaining members, by rotary movement of said fold above the end portion of said line of folding in proximity to said retaining member, the insertible portion extending along a considerable portion of each of two edges of said last mentioned fold, one of which edges is adjacent said line of folding, the other edge being opposed to said line of folding, said retaining members exerting a holding force on said fold longitudinally and transversely and holding means on said sheet adapted to be utilized after folding
- 45 to hold the same folded.
9. In a device of the character described, a sheet of metal foldable to form two or more folds, one of said folds having a stationary retaining member permanently fastened thereto so as to form with said fold a permanent pocket of which the said fold constitutes the under side, and the retaining member the upper side, one transverse extremity of said retaining member being intermediate the ends of said sheet of material, said retaining member being disposed in its entirety at one side of a line of folding, said retaining member being attached along one of its principal dimensions in proximity to a considerable portion of an edge of said fold, which edge is adjacent said line of folding, and fastened along one of its other dimensions transversely to said last mentioned edge, another fold of said sheet beginning at said line of folding and extending therefrom in the other direction from the fold having the said retaining member, said retaining member adapted to receive a considerable portion of the edge of

said last mentioned fold, said edge corresponding to said edge of the first mentioned fold in proximity to which the said retaining member is attached, both of said edges being adjacent said line of folding.

10. In a device of the character described, a sheet of material foldable to form two or more folds, one of said folds having a stationary retaining member permanently fastened thereto so as to form with said fold a permanent pocket of which the said fold constitutes the under side, and the retaining member the upper side, one transverse extremity of said retaining member being intermediate the ends of said sheet of material, said retaining member being disposed in its entirety at one side of a line of folding, said retaining member being attached along one of its principal dimensions in proximity to a considerable portion of an edge of said fold, which edge is adjacent said line of folding, and fastened along one of its other dimensions transversely to said last mentioned edge, another fold of said sheet beginning at said line of folding and extending therefrom in the other direction from the said fold having the said retaining member, said retaining member adapted to receive a considerable portion of the edge of said last mentioned fold, said edge corresponding to said edge of the first mentioned fold in proximity to which the said retaining member is attached, both of said edges being adjacent said line of folding, and said retaining member being less in area than said first mentioned fold.
11. In a device of the character described, a sheet of material foldable to form two or more folds, one of said folds having a permanent and stationary retaining member superimposed thereon, extending in one of its principal dimensions in proximity to a considerable part of an edge, which edge is adjacent a line of folding, and leaving the remainder of said sheet exposed, another fold being of a size to extend beyond the bounds of the exposed portion of the first mentioned fold and above the retaining member, a portion of such extension being insertible beneath the retaining member, a cut in the sheet along said line of folding at the end thereof to enable the aforesaid portion of the last mentioned fold to be in-

serted beneath such retaining member, and a holding flap on said sheet adapted to be utilized after folding, to hold the same closed.

12. In a device of the character described, a sheet of material foldable to form two or more folds, one of said folds having a permanent and stationary retaining member superimposed thereon, one of the principal dimensions of said retaining member being of the same length as, and extending in proximity to, an entire edge of said fold, which edge is adjacent a line of folding, and leaving the remainder of said sheet exposed, another fold being of a size to extend beyond the bounds of the exposed portion of the first mentioned fold and above the retaining member, a portion of such extension being insertible beneath the retaining member, a holding flap on said sheet adapted to be utilized after folding, to hold the same closed.

13. In a device of the character described, a sheet of material foldable to form two or more folds, one of said folds having a permanent and stationary retaining member superimposed thereon, said retaining member extending along two of its principal dimensions, in proximity to a considerable portion of each of two contiguous edges thereof, one of which edges is adjacent a line of folding, the other edge being opposed to said line of folding, the said fold being open along the entire other edge thereof which is adjacent said line of folding, another fold being insertible beneath the retaining member by a rotary movement of said fold about the end portion of said line of folding in proximity to the retaining member, and adapted to engage entirely and immediately upon the inner side of the first mentioned fold, said retaining member exerting a holding force on said fold longitudinally and transversely, and holding means adapted to hold the same folded.

In testimony that I claim the foregoing as my invention, I have signed my name in presence of two subscribing witnesses.

NATHAN OTTINGER.

Witnesses:

F. Hogg,
D. LEWIS MATTERN.

It is hereby certified that in Letters Patent No. 1,242,968, granted October 16, 1917, upon the application of Nathan Ottinger, of New York, N. Y., for an improvement in "Correspondence Devices," an error appears in the printed specification requiring correction as follows: Page 5, line 108, claim 9, for the word "metal" read *material*; and that the said Letters Patent should be read with this correction therein that the same may conform to the record of the case in the Patent Office.

Signed and sealed this 12th day of March, A. D., 1918.

[SEAL.]

R. F. WHITEHEAD,

Acting Commissioner of Patents.

Cl. 229—92.5.
